Primary Examiner — Darlington Ly

(57) **CLAIM**

The ornamental design for an electric wrench, as shown and described.

DESCRIPTION

FIG. 1 is a top-front perspective view of an electric wrench embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of an electric wrench taken from the circled part in FIG. 1.

The broken lines in the drawings depict portions of the electric wrench that form no part of the claimed design.
